UNITED STATES PATENT OFFICE.

RICHARD W. UHLIG, OF ARLINGTON, NEW JERSEY, ASSIGNOR TO ALLEN TYPEWRITER COMPANY, OF ALLEN TOWN, PENNSYLVANIA, A CORPORATION OF PENNSYLVANIA.

TYPEWRITING MACHINE.

1,410,854.

Specification of Letters Patent. Patented Mar. 28, 1922.

Application filed August 1, 1917. Serial No. 183,866.

To all whom it may concern:

Be it known that I, RICHARD W. UHLIG, a citizen of the United States, and a resident of Arlington, in the county of Hudson and 5 State of New Jersey, have invented certain new and useful Improvements in Typewriting Machines, of which the following is a specification.

This invention relates to typewriting machines, and particularly to means to impart 10 retractive movement to a platen carriage letter space distances, and which is commonly termed "back spacing", and it is the object of the invention to provide improved mechanism of this character which is simple, cheap 15 and novel in construction and efficient in operation.

In carrying out the invention I provide the platen carriage, normally urged or moved 20 in one direction under the influence of a spring, with a rack to extend longitudinally thereof and with which rack a pinion meshes, said pinion being rotatable with a ratchet wheel of an escapement mechanism 25 operable upon each impression making operation through spacing and detent dogs to feed the carriage letter space distances, and provide means operable by a to and fro movable slide or lever to impart intermittently 30 reverse movement to the ratchet wheel of the escapement mechanism and the pinion rotatable therewith and thereby retract the platen carriage letter space distances.

In the drawings accompanying and forming 35 a part of this specification Figure 1 is a sectional side elevation of a typewriting machine with an embodiment of my invention.

Figure 2 is a plan view of the escapement mechanism and my improved means to impart 40 part retrograde movement to the ratchet wheel of the escapement mechanism, the parts being shown in normal inoperative position.

Figure 3 is a view similar to Figure 2 but 45 showing the position of the parts as reverse rotary movement is imparted to the ratchet wheel of the escapement mechanism.

Figure 4 is a similar view to Figure 2 but 50 showing the parts in position as reverse rotary movement has been imparted to the ratchet wheel of the escapement mechanism one tooth space; and

Figure 5 is a detail of pawl and ratchet mechanism to impart reverse movement to the escapement wheel.

55

Similar characters of reference designate like parts throughout the different views of the drawings.

I have shown an embodiment of my invention in connection with a typewriting machine in which impression devices carried by typebars 6 pivotally supported in a segment 7 strike rearwardly against a platen 8 rotatably supported in a to and fro movable carriage 9, said carriage being normally urged 60 or moved in one direction by a spring 10 one end of which is connected to the carriage and the other end to a fixed part of the machine. The typebars are actuated by depressing key levers 11 pivotally supported, 65 as at 12, in transverse slots in a cross bar 13 extending transversely of the framework F, and connected to the typebars by links 14.

A rack 15 pivotally carried by and extending longitudinally of the carriage meshes 70 with a pinion 16 fixed to a shaft 17 supported to rotate on a vertical axis in brackets 18, 19 fixed to and extending forward from the back of the framework, and through which rack and pinion the carriage is fed or ad- 75 vanced intermittently step by step upon the actuation of the typebars. The pinion 16 is rotated step by step to feed or advance the platen carriage through escapement mechanism comprising an escapement wheel 21 80 fixed to and rotatable with the shaft 17 and pinion 16 and is advanced or rotated in the direction of the arrow (Figures 2, 3 and 4) through the influence of the carriage spring by a fixed detent dog 22 and a pivoted spacing dog 23 mounted on a carrier 24, said carrier being loose on a rock shaft 25 and normally maintained in engagement with a stop 25' by a spring 23'. The spacing dog 23 is mounted upon the carrier through a support 85 26 pivoted upon the carrier and to which the dog 23 is pivotally connected, as at 27, to have movement with the support and independent thereof for a purpose hereinafter described.

Movement is imparted to the dog carrier 90 24 to actuate the feed dogs through the rock shaft 25 by a universal bar 29 extending transversely of the framework and carried

100

by arms 30 fixed to and extending forward from the rock shaft 25. The universal bar engages over the projecting ends 31 of the key levers 11 and upon the depression of said levers to actuate the typebars (or the actuation of a word spacing bar not shown) the universal bar is lifted to the dotted line position shown in Figure 1 thereby rocking the shaft 25 causing a finger 34 fixed thereto and engaging below the dog carrier 24 to lift the latter thereby throwing the fixed dog 22 into engagement with the tooth of the escapement wheel engaged by the spacing dog 23 and then the latter out of engagement with said tooth, the same being moved to position to be engaged by the next succeeding tooth of the escapement wheel by a spring 23' through its support 26. When the finger key lever is released the universal bar is returned by its spring 35 and the dog carrier by the spring 23', thereby advancing the carriage a letter space distance.

To back space the platen carriage against the influence of its spring 10 pawl and ratchet mechanism is provided to impart rotative movement to the pinion 16 and connected escapement wheel 21 and by such reverse movement of the escapement wheel counteractive movement to the feeding dogs, comprising a ratchet wheel 38 fixed to the shaft 17 below and juxtaposed to the escapement wheel 21, said wheel preferably being of less diameter than the escapement wheel but having the same number of teeth. A slide 39 has a part 40 at the forward end extending through and slidably engaging in the forward end of the framework and provided with a finger piece at the projecting end, with the opposite end bent at right angles, as shown at 41, slidably engaging and guided between the ratchet wheel 38 and the shaft support 34 with a slot 42 therein through which the shaft 17 extends to permit of backward and forward movement of the slide. The slide pivotally carries a pawl or dog 43 to co-operate with the ratchet wheel 38 when the slide is moved backward to rotate said wheel and the shaft 17 with the connected escapement wheel and pinion 16 in a direction reverse to that indicated by the arrow. The pawl is caused to engage with a tooth of the ratchet wheel 38 by a spring 44, said spring normally maintaining the pawl in position with a part 44' thereof in engagement with a stop 38'. The slide is retracted and maintained in its forward position by a spring 45 connected at one end to the slide and at the opposite end to the lever supporting cross bar 13 (Figures 1 and 2). During the initial backward movement of the slide with the escapement wheel arrested by a tooth 46 thereof engaging with the spacing dog 23, as shown in Figure 2, as the pawl 43 engages with a tooth of the ratchet wheel 38, said latter wheel is rotated a dis-

tance more than one tooth space causing the succeeding tooth 47 of the escapement wheel (Figure 2) to engage with and swing the spacing dog 23 on its pivot against the action of a spring 49 until said pawl or dog 70 rides over the tooth 47 (Figure 3) to assume a position in the tooth space at the right of said tooth as viewed from Figures 2, 3 and 4 when the dog is returned to its initial position to be engaged by the tooth 47 75 of the escapement wheel when the slide 39 is released and retracted by its spring 45, and the parts are again in position to be actuated through the operation of the universal bar 29 upon the actuation of the key levers or word space bar to advance the carriage letter space distances. It will be obvious that during the retrograde movement of the ratchet wheel 38 the connected escapement wheel is also moved back one space, 85 and thereby the carriage back spaced a distance equal to a letter space.

Having thus described my invention, I claim:

1. In a typewriting machine, the combination with the framework and a longitudinally movable platen carriage including a rack extending longitudinally thereof and a spring to urge the carriage in one direction, of a vertical shaft; a pinion fixed to the upper end of said shaft meshing with the carriage rack; an escapement wheel on said shaft; dogs co-operating with the escapement wheel and operable to advance the carriage letter space distances; a ratchet wheel 90 fixed to the lower end of said shaft; a slide mounted substantially midway of the machine and extending from the front to the rear and having longitudinal to and fro movement, said slide having a slot in the rear portion for the passage of the shaft to guide the slide in its movement; a pawl carried at the rear end of said slide to co-operate with the ratchet wheel; a spring to normally urge and maintain the slide in its forward position and thereby the pawl out of engagement with the ratchet wheel; and said pawl adapted to engage a tooth of said wheel to advance the same one tooth space upon each rearward movement of the slide 95 for the purpose specified.

2. In a typewriting machine, the combination with a longitudinally movable carriage and normally urged in one direction, of escapement mechanism including an escapement wheel and dogs to co-operate therewith to feed the carriage letter space distances; a ratchet wheel rotatable with the escapement wheel; a longitudinally reciprocal slide extending from the front to the rear of the machine; a spring to normally urge the slide forward; a pawl pivotally carried at the rear end of the slide having a pallet to engage a tooth of the ratchet wheel when the slide is moved rearward to rotate 120

125 130

the ratchet wheel and thereby the escape-
ment wheel in reverse direction to retract
the carriage; a stop carried by the slide;
and a spring to maintain the pawl in en-
gagement with the stop and in position to
engage a tooth of the ratchet wheel when
the slide is moved rearward and adapted to

permit the pawl pallet to ride over a tooth
of the ratchet wheel when the slide is moved
forward by its spring. 10

Signed at New York city, in the county
of New York, and State of New York this
third day of July, 1917.

RICHARD W. UHLIG.
